UNITED STATES PATENT OFFICE.

FRANK DE SILVA, OF BOSTON, MASSACHUSETTS.

VESTIBULE-DIRECTORY.

SPECIFICATION forming part of Letters Patent No. 703,560, dated July 1, 1902.

Application filed April 8, 1902. Serial No. 101,949. (No model.)

To all whom it may concern:

Be it known that I, FRANK DE SILVA, a citizen of the United States of America, and a resident of Boston, in the county of Suffolk 5 and State of Massachusetts, have invented certain new and useful Improvements in Vestibule-Directories, of which the following is a specification.

My invention relates to improvements in directories for bulletins placed in the vestibules or halls of commercial blocks, apartment-houses, hotels, &c., to locate the offices and apartments and the occupants thereof, and it particularly appertains to the class of 15 directories whereon are located numerically the floors and alphabetically the numbers and addresses of the various tenants; and the objects of my improvements are, first, to provide a series of interchangeable independent 20 frames, but preferably united in pairs, which may be added to uniformly when an increase of the directory is subsequently desired; second, the arrangement of certain name-bearing tablets alphabetically without the necessity of disturbing adjacent frames or 25 obstructing the view thereof; third, the manner of confining said tablets within the glass frontage and against the adjustable back board embraced by each frame; fourth, the 30 employment of a secondary backing to regulate said adjustable back board in propinquity to the glass front, and in other essentials hereinafter enumerated, and especially 35 designated in the claims.

A more specific description of the remaining features of my improved invention will be obtained through reference to the drawings, forming part of this specification, where-in—

Figure 1 is a front elevation of one of the 40 directories composed of two individual frames and glasses united. Fig. 2 represents a rear elevation of the same. Fig. 3 is an enlarged transverse section of a single assembled 45 frame, exhibiting the double backs and manner of adjusting the same. Fig. 4 illustrates a fragmentary perspective of one of the back boards to exhibit the attached reflexed retaining edge strips supporting the name-tablets. Fig. 5 exhibits an aggrouped section 50 organized for reference with one tablet-frame opened to disclose the construction of the

back and display the bevels on the longitudinal rear edges of the glass panels. Fig. 6 designates a vertical transverse section on dashed line 6 of Fig. 5, and Fig. 7 a horizontal section on dashed line 7 of Fig. 5.

Corresponding letters of reference designate similar features throughout the several views, referring to which—

A A are right and left frames holding duplex-beveled glass panels. These frames are united preferably as at B, or they may be hinged at the top, so as to swing outwardly. Each of said frames is provided with a recess or rabbet C contiguous to the front to receive and support the glass panels D, which in addition to the ornamental bevel around the exterior edges are further provided with a bevel E E at a more acute angle with the plane of the rear surface on each of the longitudinal rear side edges F F. (Well observed in Fig. 2.) The office of said bevels E E is to form, in connection with the inner faces G G of the side of each frame, triangular-shaped spaces H H, Fig. 7, which receive the inwardly-reflexed retaining-pieces I I, comprising metal or wooden strips secured to each of the corresponding longitudinal edges of the adjustable back boards J J, 80 and which lie contiguous to the said bevels E E when the glass fronts are closed, as in Fig. 5. These back boards J J are adjusted so as to lie in juxtaposition to the glass panels D by several screws L L, having integrally an annular collar L' and a slotted threadless head passing through the back board and its retaining surface from the rear side, the threaded members entering the fixed backings K K, which are firmly secured to the top 90 and bottom of the main frame P, as at M M, Fig. 6, insuring an intervening space for the back-board adjustment, said screws are adjusted from the front of the back boards in the ordinary manner after removing the individual name-plates which conceal the slotted heads. By the employment of this particular form of adjusting-screws no registering-pins are necessary, as they obviously combine the office of registering and adjusting. 95 This manner of adjustably confining the back board and backing also obviates any tendency that may be inherent to warp, and thus become displaced in their relation with said in-

closing frames or glass fronts. The adjustable back boards J J are further provided with a retaining-surface N, adjacent to the rear side of the glass fronts, which may consist of fabric or may be flocked or otherwise produced, the essential character of which is to restrain the tablets O from shifting and to insure a yielding pressure, so as to retain the uniform alinement and surface of the aggregated name-tablets for inspection. This feature, however, may be replaced by the application of a corresponding surface to the under sides of each tablet.

In the practical arrangement of my improved directory, assuming a necessary addition or rearrangement of the lettered or figured tablets, one or more of the frames are unlocked and swung outwardly, permitting access to the name-tablets, when any substitution or rearrangement may be easily and quickly effected by withdrawing the pliable tablets comprising any flexible material from the reflexed retaining-pieces I I and without the necessity of rearranging the backings.

In the final arrangement of the aggregated frames A A they may be inclosed in a cabinet or surrounded by an ornate (glassless) frame P, Fig. 5, which will permit access to the individual sets of panels, sustain them, and impart character to the assemblage.

I am aware that similar directories or bulletins have been heretofore used, as evidenced in Letters Patent No. 560,878 of May 26, 1896, and others, wherein the flexible name-plate, the frames supporting them, and the back boards having a retaining-surface are shown; but I am unaware of the use of a bevel formed upon the rearward longitudinal edges of the glass frontage for the purpose defined, the reflexed attached pieces supporting said tablets, a back board that is adjustable from the front or the fixed backing coacting by the described means to effect the adjustment of the back board with its sustained tablets against the glass frontage. I therefore consider said features as new, and while I have described and illustrated the preferred construction I desire not to be confined to the literal interpretation herein de-

fined, but may employ such equivalents therefor as will come within the fair scope and spirit of my invention, which, having thus described,

I claim—

1. In a vestibule or hall directory, the glass panel having a bevel formed on each of its longitudinal rearward edges, the adjustable back board provided with reflexed retaining-strips on their longest edges adjacent to said bevels adapted to support the flexible tablets, and means to regulate the distance of the back boards to or from said glass panels substantially in the manner specified.

2. A vestibule or hall directory, comprising individual glass panels provided with bevels on their rearward longest edges, the adjustable back boards having their longitudinal edges provided with means for retaining temporarily certain name-plates, the fixed backing coacting with said adjustable back boards, and means as hereinbefore described to frontally adjust and secure said back boards with their assembled name-tablets with gentle pressure against the glass frontage substantially in the manner and for the purpose set forth.

3. In combination, the glass panels provided with bevels on their rear longitudinal edges, the reflexed retaining-strips lying contiguous to said bevels in a manner to collectively or singly sustain the name-tablets, the adjustable back boards adapted to support said reflexed strips and means to restrain shifting of said tablets, the fixed backing coacting with the back boards and the adjusting-screws having a circular bearing to regulate the distance intervening between said back boards and the rear faces of the glass panels forming the front of the organized bulletin substantially as specified.

In testimony whereof I have hereunto signed my name, in the presence of two subscribing witnesses, at Boston, Massachusetts, this 5th day of April, 1902.

FRANK DE SILVA.
